CHILD'S WHEELED PNEUMATIC TOY

Jesse J. Morsch, Douglas, Wyo.

Application March 28, 1952, Serial No. 279,075

6 Claims. (Cl. 124—13)

1

This invention relates to a mechanical toy, and has for its principal object the provision of a wheeled toy which, when pushed or pulled, will develop air pressure, and which can be used to fire a toy cannon and selectively operate other air-operated devices, such as a toy flagman, a flying flag, a firing indicator, etc.

A further object is to provide a spring-loaded air reservoir which will automatically regulate the air pressure to any desired degree and provide a safety valve to prevent reservoir rupture.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a side view of the improved mechanical toy;

Fig. 2 is an enlarged bottom view thereof;

Fig. 3 is a top view thereof;

Fig. 4 is a longitudinal section, taken on the line 4—4, Fig. 3;

Fig. 5 is a detail, enlarged section, taken on the line 5—5, Fig. 3;

Fig. 6 is a longitudinal section, taken on the line 6—6, Fig. 3;

Fig. 7 is a longitudinal section, taken on the line 7—7, Fig. 3; and

Fig. 8 is a cross-section, taken on the line 8—8, Fig. 3.

The improved mechanical toy consists of an inverted, pan-shaped housing 10 mounted on a drive wheel 11, an idler wheel 12, and a trailing wheel 13. The housing is provided with a suitable handle socket 81 for receiving a handle 64. The bottom of the housing 10 is partially closed by means of a U-shaped bottom plate 14 secured therein adjacent one extremity thereof in any desired manner. The bottom plate 14 supports wheel brackets 15 carrying an axle 16 for the idler wheel 12 and bearings 17 for rotatably supporting a driving axle 18 in alignment with the axle 16.

The driving axle 18 terminates in a crank disc 19 provided with a plurality of threaded crank-receiving openings 20 into any one of which a crank pin 21 may be threaded. A crank fitting 22 is mounted on the crank pin 21. The fitting 22 is mounted on a pump piston rod 23 operating in a reciprocating pump cylinder 24. The pump

2

cylinder 24 is tiltably mounted on a pump shaft 25 extending across the forward extremity of the housing 10.

The air pumped by the pump cylinder 24 is conducted through a conventional check valve 82 and through a feed tube 26 to a cylindrical air reservoir 27. An open-ended, cylindrical sleeve 28 extends through one extremity of the reservoir 27. A plunger 29 is slidably mounted in the sleeve 28 upon a plunger rod 30 which is connected with an actuating lever 31 projecting from a cross shaft 32 extending across the housing 10. A spring lever 33 also extends radially from the cross shaft 32, to which an elongated extremity on a tension spring 34 is connected. The other extremity of the tension spring 34 is attached to a tension-adjusting screw 35 extending through one extremity of the housing 10 by means of which the tension in the spring 34, and the pressure in the reservoir 27, may be adjusted.

It can be seen that as the pressure of the air in the reservoir 27 increases, it will act to force the plunger 29 outwardly in the sleeve 28 so as to rotate the cross shaft 32 against the resistance of the tension spring 34. When the plunger reaches a predetermined point, it will uncover a safety port 83, allowing any additional air to escape to the atmosphere.

The rotative movement of the cross shaft 32 is utilized to raise an arm 36 of a signal man 37 mounted on the housing 10. The signal man consists of two cut-out sheet metal sheets arranged in parallel relation and supporting an arm pivot pin 38, to which the arm 36 is secured. An arm lever 39 projects from the pin 38 and is connected by means of a connecting wire 40 with an arm-actuating lever 41 mounted on a counter-shaft 43, which is rotated from an actuating lever 45 affixed to the cross shaft 32 through the medium of a connecting rod 44. Thus, as the air pressure increases in the reservoir, the arm of the signal man will slowly raise to display a firing flag 42.

A firing indicator casing 45 is mounted on the housing 10 enclosing a rotatable indicator drum 46 mounted therein and visible through a window 47. The drum 46 carries suitable indications, such as "Load," "Aim," and "Fire," which are exposed through the window 47 as the drum 46 rotates. The drum is rotated through the medium of a connecting link 48 extending to a drum lever 49 projecting from the cross shaft 32. Thus, it can be seen that as the pressure builds up in the reservoir, the drum will be rotated to selectively display the indications thereon.

A tubular gun barrel 50 is mounted to swing

in a vertical plane between two pipe-supporting standards 51. Air is conducted to one or both the standards 51 through the medium of a gun hose 52 leading directly from the air reservoir 27. The air flows into an air chamber 53 in the rear of the barrel. A valve seat 54, closed by a disc valve 55, prevents the air from entering the barrel 50. The valve 55 is constantly urged to its seat 54 by a spring 56 surrounding a valve stem 57 projecting from the valve through a packing gland 58 on the rear of the barrel 50.

It can be seen that when the valve stem 57 is pulled rearwardly, the entire air supply of the reservoir will flow past the valve 50 to force any desired projectile, such as indicated at 59, from the barrel. The valve stem 57 may be pulled rearwardly through the medium of a trigger lever 60 to which a flexible cord 61 is connected. The cord 61 extends over suitable guide pulleys 62 and through a guide tube 63 upwardly along the handle 64, terminating in a slack-removing spring 65 connected to a cross piece 60 on the handle 64. The string is provided with a finger grip bead 66 to afford a better finger grip.

The vertical firing angle of the gun barrel 15 can be adjusted by means of a crank 67 mounted on a crank shaft 68 extending between brackets 69 supported from the two pipe standards 51. The crank shaft 68 carries a suitable toothed gear 70 which engages an arcuate gear segment 71 mounted below the gun barrel 15.

A hollow, tubular flagstaff 72 is mounted on the housing 10 and supports a flag 73 of lightweight, flexible material, such as silk or the like. Two L-shaped nozzles 74 project from the flagstaff 72 toward and at each side of the flag 73. The lower extremity of the flagstaff 72 is connected by means of a flexible hose 75 with the reservoir 27.

The hose 75 passes through a hose valve yoke 76 having a sliding hose clamp 77 which is urged by a spring 84 to normally squeeze the hose closed to prevent air from passing therethrough. The clamp 77 may be pulled away from the hose by means of a second cord 78 which extends from the housing 10 through a second guide tube 79 and terminates on the handle 64 in a bead and spring similar to the bead 66 and the spring 65 previously described.

It can be readily seen that as the cord 78 is drawn upon, it will allow air to flow from the reservoir, through the hose 75, flagstaff 72 and nozzles 74, to provide air jets against the opposite faces of the flag to create a life-like, waving motion therein.

If it is desired to adjust the pump to more rapidly fill the reservoir, the crank pin 21 may be moved to one of the pin openings 29 further from the axis of the disc 19.

While a specific form of the improvement has been described and illustrated herein, it is to be understood that the same may be varied, within the scope of the appended claims, without departing from the spirit of the invention.

Having thus described the invention, what is claimed and desired secured by Letters Patent is:

1. A wheeled toy comprising: a body housing; wheels supporting said housing; an air-pumping mechanism mounted on said body housing connected with and operable from one of said wheels;

a reservoir mounted in said body housing; means conducting air from said pumping mechanism to said reservoir; a sleeve mounted in fixed relation to said reservoir and receiving air under pressure from said reservoir; a plunger reciprocal in said sleeve and adapted to be moved in one direction by the air in said reservoir; a spring urging said plunger in the other direction; a gun barrel mounted on said housing; a conduit conducting air from said reservoir to said gun barrel; a valve in said gun barrel controlling the admission of air thereto; manual means for opening said valve; and spring means for closing said valve.

2. A wheeled toy as described in claim 1 having a handle extending rearwardly and upwardly from said housing for pushing the latter; and a flexible member connected with said valve and extending upwardly along said handle within reach of the user thereof.

15 3. A wheeled toy comprising: a housing; a drive wheel; an idler wheel, said wheels supporting said housing; an air pump mounted in said housing; a crank rotated by said drive wheel; a piston rod extending from said crank to said

25 pump for actuating the latter; an air reservoir mounted in said housing; an air conduit communicating between said pump cylinder and said reservoir; a check valve in said air conduit acting to prevent the return of air to said pump

30 cylinder; a hollow gun-supporting standard arising from said housing; a tubular gun barrel supported by and in communication with the hollow standard; means conducting air from said reservoir to said hollow standard; and valve

35 means controlling the discharge of air from said hollow standard to said gun barrel.

4. A wheeled toy as described in claim 3 having an open-ended cylindrical sleeve extending through the wall of said reservoir; a plunger slidably mounted in and closing said sleeve; a spring urging said plunger against the air under pressure in said reservoir; and indicating means on said housing and means for transmitting movement from said plunger to said indicating means for causing the latter to indicate the pressure in said reservoir.

5. A wheeled toy as described in claim 4 having means for limiting the air pressure in said reservoir to predetermined pressure comprising: 50 a port formed in the wall of said sleeve and communicating exteriorly of said reservoir and positioned to be uncovered by said plunger as the latter moves away from said reservoir against the action of said spring.

6. A wheeled toy as described in claim 5 having means operable from the exterior of said housing for varying the effective reaction of said spring.
